UNITED STATES PATENT OFFICE.

ALEXANDER DOM, OF CINCINNATI, OHIO, ASSIGNOR TO THE SAMUEL C. TATUM COMPANY, OF CINCINNATI, OHIO, A CORPORATION OF OHIO.

BINDER.

1,241,610.

Specification of Letters Patent.

Patented Oct. 2, 1917.

Application filed May 10, 1916. Serial No. 96,504.

To all whom it may concern:

Be it known that I, ALEXANDER DOM, a citizen of the United States, and residing at Cincinnati, in the county of Hamilton 5 and State of Ohio, have invented a new and useful Improvement in Binders, of which the following specification is a full disclosure.

My invention relates to an improvement 10 in what is commonly known as a "snap-binder" designed to hold loose leaves in book form under spring compression of the covers, the spring providing the normal inward snap tension and opening to accommodate and retain a greater or lesser number 15 of leaves.

The object of the invention is to provide a hinged construction for the binding element having no inward extensions but presenting a smooth or flat surface in rear of the clamped portion of the leaf margins, enabling the latter to be properly compiled and alined and placed in extreme rearward position between the binding elements, abutting 25 the smooth or flat surface of the hinged structure, the lateral extensions of which project rearwardly or exterior of the binder back.

Another object of the invention is to provide 30 such a hinged construction with an opening limit member, also supported and extending rearwardly of the binder back.

The features of the invention are more fully set forth in the description of the accompanying drawings, forming a part of 35 this specification, in which:—

Figure 1 is a side elevation of the binder.

Fig. 2 is a section through the hinged portion of the binder in open position, showing 40 the stop member in full lines.

Fig. 3 is an elevation from the right side of Fig. 2.

Fig. 4 is a rear elevation, partly broken away, to show the stop member.

Fig. 5 is a detail perspective view of one 45 of the stop members.

The binder preferably is a sheet metal structure comprising the top cover members 2, 2', hinged together by eyes 3 and hinge- 50 rod 4 toward the back of the binder, the hinged portion 2 constituting one of the binding elements. The rear margin of the cover member 2 is formed with a down-turned flange 5 terminating with a series 55 of outwardly turned eyes 6 horizontally

aligned. The under cover 1 constitutes the coacting binder element and is preferably integral. Its rear end is formed with up-turned flanges 7 terminating with a series of outwardly or rearwardly looped eyes 8, 60 horizontally aligned and similar in form to the eyes 6, the upper and lower sets of eyes being alternately spaced to intermesh and bring the two sets of eyes into registration for supporting the hinge rod 9, which is 65 thus held on the rear or outer portion of the binder back, so that the inner surfaces 10, of the two flanges present a smooth or flat contour which will not interfere with the compilation and alinement of the rear 70 edges of the leaves 11, the hinge rod and the eyes being rearwardly extended and housed within the binder back 12.

Said back is a resilient bow, the extremities of which engage or are attached to the 75 binder elements 2 and 6, the spring back 12 in one position of the binding elements exerting a normal inward tension, tending to force them together to grip the interposed leaves, and in the other position the 80 tension reverses to open up the binding elements. Of course it will be understood that the inward tension of the back 12 tends to close the binder with a snap, on one side of the center of movement, and tends to throw 85 the binder elements apart when they are moved beyond this center. In order to provide a limit to this separating movement of the binder elements under the influence of the spring back, I support on the hinge rod 90 one or more struts 13, having the semi-eyes 14 which engage over the hinge rod at appropriate spaces formed between the two cover flanges, the ends 15 of the struts being rearwardly extended and housed within the 95 spring back, as shown in Fig. 1, which brings the rounded or bearing portions of the struts into alinement with the eyes of the flanges flush with the inside surface of the binder back, so as to preserve the regularity of the said inner surface.

When the covers are opened up past the center, the spring will force them apart until the flanges of the covers are stopped by contact with the strut ends 15, as shown in 105 Fig. 2, thus limiting the outward swing and holding the binding elements in a predetermined leaf receiving position and when the binding elements are compressed they will snap to closed or binding position. 110

The preferred method of engaging or attaching the marginal edges of the spring back 12 to the cover members 2 and 6 consists of providing two strips 20, 21, which are secured to the flanges 5 and 7 and extend outwardly beyond the outer surfaces of the cover members, thereby forming a pocket or groove into which the inturned marginal edges 22 of the spring back engage.

10 I claim:

1. In a device of the nature disclosed, top and bottom leaf binder members formed with down and up turned flanges, terminating in outturned, horizontally alined intermeshing bearings, a hinge rod supported in said bearings, a stop member on said rod with its ends extended rearwardly of said hinge rod in the path of movement of the opening binder members, to determine the

leaf receiving position, and a spring back 20 connecting said binder members and inclosing said rod and stop.

2. In a device of the nature disclosed, two leaf binder members having inturned flanges terminating with intermeshing hinge elements, a hinge rod joining said hinge elements, a stop member on said rod extending outwardly to intercept the inturned flanges to limit the opening movements of the binder members, and a spring back connecting the binder members.

In witness whereof, I hereunto subscribe by name, as attested by the two subscribing witnesses.

ALEXANDER DOM.
